UNITED STATES PATENT OFFICE.

LIPA POLINKOWSKY, OF ANTWERP, BELGIUM, ASSIGNOR TO WESTERN ELECTRIC COMPANY, INCORPORATED, OF NEW YORK, N. Y., A CORPORATION OF NEW YORK.

MACHINE-SWITCHING TELEPHONE SYSTEM.

Application filed November 8, 1919. Serial No. 335,464.

To all whom it may concern:

Be it known that I, LIPA POLINKOWSKY, a citizen of Russia, residing at Antwerp, Belgium, have invented certain new and useful

5 Improvements in Machine-Switching Telephone Systems, of which the following is a full, clear, concise, and exact description.

This invention relates to telephone systems and more particularly to systems in 10 which automatic switching apparatus is employed for establishing talking connections between subscribers' lines.

The object of the invention consists in the provision of improved means, in a system 15 where a series of automatic switches are selectively controlled by means of a switch controlling mechanism, for immediately associating such mechanism with a calling line when a call is initiated upon said line.

20 A feature of the invention consists in the provision of means, in a system comprising a line selector and a series of group selector switches for extending calling lines together with a switch controlling mechanism adapted to be set by the calling subscriber to control said selector switches, whereby said

25 controlling mechanism is immediately associated with the calling line on the initiation of a call, and may be set by the calling subscriber while said line selector is operated to select the calling line. According to this feature the calling subscriber, by means of his sender, may partly set up the controlling mechanism during the time the line selector

30 is finding his line, whereafter the continued operation of said sender serves to send impulses over the circuits of the line selector to complete the setting of the controlling mechanism.

35 A further feature consists in the provision of means, in a system of this character involving a switch controlling mechanism consisting of a plurality of registers for registering line numbers, whereby the designation

40 of a calling line is automatically registered on said registers which thereupon operate to directly control the line selector to the calling line during the time the calling subscriber is proceeding to register the called line designation on said register

45 controlling mechanism.

A still further feature is the provision of means whereby a portion of the registers of the controlling mechanism may be set by 50 the calling subscriber during the time the

remainder of said registers are being automatically positioned in accordance with the designation of the calling line to control the operation of the line selector switch, said latter registers being also available to the calling subscriber for registering the remainder of the called line designation as soon as they have completed their function of controlling said line selector.

Such other features as are contemplated by the present invention will become more apparent from the following description and the appended claims.

In the drawings, Fig. 1 shows two subscribers' lines of a group of calling lines together with the circuits of a common connecting apparatus for associating such lines with an idle register controlling mechanism. Fig. 2 shows detailed circuits of a line selector switch for connection with the calling lines and a first group selector switch for extending said lines in the direction of other group selectors of which two are diagrammatically shown in this figure. Fig. 3 shows a register controlling mechanism for controlling the selective operation of the line selector and group selectors shown in Fig. 2. This figure also illustrates a cord finder switch for associating a selected controlling mechanism with a line selector and a first group selector having access to the particular group of lines which contains the calling lines.

In the system embodying the features of this invention there is shown a register controlling mechanism for controlling the selective operation of a series of automatic selector switches for extending connections from a calling line to a called line. Since this system as disclosed is of the full automatic type, the usual preliminary or line selector switch is utilized to first extend the calling line to group selector switches. The usual practice has been to associate the register controlling mechanism with the circuits of the first group selector switch whereby such mechanism is not placed under the control of the calling subscriber's line until after the line selector has found the calling line. In order that the calling subscriber may not have to wait until the line selector has found his line, before he can proceed to transmit impulses to the controlling mechanism, the present invention contemplates an arrangement in which

such controlling mechanism is immediately associated with the calling line so that the calling subscriber may proceed to set up the registers thereof prior to the time 5 that the line selector has moved to the terminals of his line. To accomplish this end the subscribers' lines are divided into groups of 200 lines, each group appearing as calling lines in the multiple terminals of 10 200 point line selector switches. Each group of 200 lines is divided into two sub-groups of 100 lines each, namely, an even-hundreds group and the next succeeding odd-hundreds group. A further sub-division is made by 15 arranging the lines in sub-groups of 20, each sub-group comprising ten lines of the first or even-hundreds and the corresponding ten lines of the second or odd-hundreds. For example, the first of these sub-groups of 20 lines would constitute the first ten lines, 0 to 9 of the first or even-hundreds and in the corresponding first ten lines, 100 to 109 of the second or odd-hundreds group. Likewise, the second sub-group of 20 lines would 20 consist of lines 10 to 19 of the zero hundred and lines 110 to 119 of the first hundred, etc. For each sub-group of 20 lines there is provided a common connecting means including a group of ten relays which correspond 25 to the units digits of each line in such sub-group. These relays are identified by the numerals 236 to 239 in Fig. 1, it being considered necessary to show only a portion thereof. In the disclosure there is shown 30 two lines 099 and 199 belonging to the same sub-group of 20 lines. As is obvious, this sub-group comprises lines 090 to 099 and 190 to 199. Common to the units relays 236 to 239 is a sequence switch 210 which, as 35 will be hereinafter described, operates under the control of said units relays to position the units register 140 of the controlling mechanism shown in Fig. 3, which in turn controls the units selective movement of the 40 line selector switch shown in Fig. 2. The tens register 130 which controls the group selective movement of the line selector switch is automatically set to a position corresponding to the designation of the group 45 of 20 lines in which the calling line appears. By this grouping arrangement the first group of 20 lines appears as calling lines in the first level of terminals in the line selector switch shown in Fig. 2. The 50 second group of 20 lines appears in the second level, the third group in the third level and so on. When, for example, a line, such as lines 099 and 199 of the tenth group of 55 20, initiates a call the particular relay of 60 the group of relays 236 to 239, corresponding to the units digit of such calling line, is energized and determines that the units register 140 is automatically set up to a position corresponding to said units digit under 65 the control of sequence switch 210. Fur-

thermore, the fact that the calling line belongs to the tenth group determines that the tens register 130 will be automatically adjusted to its ninth position as will herein-after be explained. The tens and units registers 130 and 140 having thus been positioned are then effective to control the line selector switch shown in Fig. 2, first to pick out the level of 20 terminals containing the calling line and then to direct its brushes 75 on to the terminals of such line.

While the line selector is being operated in this manner to find the calling line, the calling subscriber may be operating his impulse sender to position the first two registers, 80 such as the thousands register 110 and the hundreds register 120, in accordance with the first two digits of the called line. As soon as the line selector has been driven to the terminals of the calling line, the mechanism shown in Fig. 1 for temporarily associating the calling line with the register controlling mechanism, is disconnected and the calling subscriber by continuing the operation of his impulse sender, sets up the tens and units registers 130 and 140 over an impulse circuit which leads through the terminals and brushes of the line selector switch. 85

The register controlling mechanism shown in Fig. 3 consists of a plurality of sequence switch registers, each having ten circuit controlling positions, one for each digit. These registers are driven under the control of the subscriber's sender to a position corresponding to the number of impulses contained in the series. After having been positioned 90 they are driven through their remaining positions, back to position 0 to control the selective operation of the respective switches. Hence it is obvious that the number of positions through which the registers are driven on passing to position 0 is the complement of the number of impulses transmitted from the subscriber's sender. In order that the 95 switches may be controlled in accordance with the digits of call numbers as listed in the directory, it is necessary to arrange the subscribers' dials to transmit the complements rather than the actual digits themselves. Moreover, the subscribers' dials are arranged to transmit a comparatively long impulse at the end of each series. For a 100 more detailed description of the purpose of designing the subscribers' dials in this manner reference is made to Patent No. 146,517 of Polinkowsky-Matthies, filed in Great Britain, October 5, 1921.

The switches and other apparatus employed in this system may be of the same general construction and operation as shown and described in the patent to F. R. McBerty, No. 1,097,868, issued May 26, 1914, and the patent to F. R. McBerty et al, No. 1,137,223, issued April 27, 1915. 105 110 115 120 125 130

For a detailed description of the operation of the present system, it will be assumed that the subscriber of line 199 wishes to converse with the subscriber of line 200. By 5 removing his receiver from the switchhook a circuit is established from ground over the contact and inner armature of cut-off relay 207, thence over the loop of the substation and returning by way of the outer armature 10 and contact of relay 207, inner upper armature and back contact of the units relay 239, inner upper armature and back contact of relay 249 through the winding of line relay 201 to battery and ground.

15 The relay 249 shown within the broken line in the upper left-hand corner of Fig. 1 corresponds to relay 239. This relay together with other relays which correspond to the relays 236 to 239, constitute a second common mechanism for associating calling lines of this particular group of 20 lines with an idle register mechanism. If 20 the calling mechanism shown in detail in Fig. 1 is busy and a second call is initiated 25 in this particular group of lines, the second common mechanism illustrated diagrammatically within the broken lines is taken for use to associate such a calling line with a second register mechanism, as shown in 30 Fig. 3.

When the line relay 201 operates, a circuit is closed from battery, outer right-hand armature and back contact of relay 211, through the winding of relay 212, contact and right-hand armature of the line relay 201, through the upper winding of the units relay 239 to ground. Relays 212 and 239 are energized. Relay 239 opens the circuit of the line relay 201 and also the 40 circuit of the line relay 202 individual to the second line of the pair 099. Relay 239 at the same time closes a circuit from ground over its lower armature, contact and lower winding, left-hand armature and back contact 45 of relay 214 through the winding of relay 215, contact and inner armature of relay 211 to battery and ground. The relay 215 energizes and provides individual test circuits for the different register sets such 50 as the one shown in detail in Fig. 3. Assuming the register set shown in Fig. 3 is idle, a circuit is closed from ground over the inner armature and contact of relay 215 through the left-hand winding of relay 216, contact 322 of sequence switch 320, back contact and right-hand armature of relay 323, contact 327 of sequence switch 320, contact 352 of sequence switch 350 to battery and ground. Relay 216 attracts its armatures and provides a holding circuit for 60 itself as follows: ground, lower armature, contact and lower winding of relay 239, left-hand armature and back contact of relay 214 through the left-hand winding 65 of relay 211, inner right-hand armature and

front contact of relay 216, through the right-hand winding of 216, through the winding of relay 323, contact 327 and contact 352 to battery and ground. Relay 211 opens the circuit of relay 215, which thereupon de-energizes while relay 323 opens the test circuit above traced so that this register set cannot be taken by another calling line. When relay 323 energizes it closes a circuit from ground, through the winding of relay 324, front contact and right-hand armature of relay 323, contact 327 and contact 352 to battery and ground. Relay 323 also closes a circuit over its left-hand armature and contact and sequence switch contact 332 (1) 80 for driving sequence switch 320 out of position 1 into position 2.

It may be well to note at this point that the circuits of the register-controlling mechanism shown in Fig. 3 are controlled by means of the two sequence switches 320 and 350. All sequence switch contacts above the horizontal broken line and to the left of the vertical broken line are controlled by sequence switch 320 and all contacts above the horizontal broken line and to the right of the vertical broken line are controlled by the sequence switch 350. The sequence switch contacts within the small broken line rectangles at the bottom of Fig. 3 are controlled respectively by the registers 110, 120, 130 and 140.

When relay 211 energizes it also opens the circuit of relay 212 which in turn deenergizes. If another call in this sub-group is initiated a units relay such as relay 249 of the second connecting apparatus may now be energized over the armature and back contact of relay 212, the armature and contact of the line relay 201 of the calling line 105 and the contact of relay 241 which corresponds to relay 211 of the apparatus shown in detail: In the manner described, relay 241 energizes in series with relay 249 and the calling line is connected to an idle controlling mechanism.

When relay 324 attracts its armature it closes an energizing circuit for stepping relay 325 from ground and battery through the winding of said relay, contact and outer armature of relay 324, front contact and outer right-hand armature of relay 216, inner right-hand armature and back contact of relay 214, front contact and inner upper armature of relay 239, contact and outer armature of cut-off relay 207 over the loop of the line to the inner armature and contact of relay 207 and ground. At the time sequence switch 320 moves into position 2, relay 331 is energized in a circuit from ground to battery, contact 326 (2) through the winding of relay 331 to ground at the back contact and armature of relay 334. Stepping relay 325 therefore closes a circuit

from ground over its armature and front contact, armature and contact of relay 331 through the left-hand winding of relay 329, armature and contact of said relay, contact 5 311 (2), through the winding of the thousands register 110 to battery and ground. A parallel circuit is also closed for the right-hand winding of relay 329 from ground and battery at the relay to the armature and ground of relay 325. The relay 329 is differential and therefore does not attract its armature when both windings are energized. The thousands register 110, however, moves out of position 0 and on closing its local 10 contact 111 short-circuits the left-hand winding of relay 329 which in turn attracts its armature. The register 110 under the control of its local contact moves into position 1. When the calling subscriber manipulates his dial in accordance with the first 15 series of impulses, the first interruption of the line circuit causes the deenergization of the stepping relay 325 which in turn opens the circuit of the right-hand winding of relay 329. Relay 329, therefore deenergizes. Upon the next closure of the line circuit, relay 325 attracts its armature and the above traced circuit for the thousands register 110 is again closed and this register moves out 20 of position 1 and into position 2. For each succeeding interruption of the line circuit during the transmission of the first series of impulses the register 110 advances one position and finally comes to rest in a position 25 corresponding to the complement of the number of the thousands digits transmitted. The last impulse of the series being comparatively long, the armature of relay 325 remains retracted for a longer period than on the preceding impulses. Relay 334, which 30 is slow-to-attract its armature, is therefore energized over the following circuit; battery, at sequence switch contact 342 (2) through the winding of relay 334 to ground at the 35 armature of relay 325. Relay 334 attracting its armature closes a circuit for driving sequence switch 320 out of position 2 and into position 5.

When the line circuit is again closed and 50 relay 325 is energized, a circuit is established from ground over the armature and front contact of relay 325, armature and contact of relay 321, left-hand winding, armature and contact of relay 329, sequence switch 55 contact 312 (5), through the winding of the hundreds register 120, to battery and ground. In the manner already described, the hundreds register 120 is driven from one position to another in response to the second series of impulses transmitted from the calling subscriber's dial and comes to rest in a position corresponding to the complement of the hundreds digit. On the last interruption of the line at the end of the second series of 60 impulses, relay 334 energizes and closes a

circuit to drive sequence switch 320 out of position 5 and into position 8. It will be noted that relay 334 has its circuit opened at the armature of relay 325 to permit of its deenergization prior to the time that sequence switch 320 can reach position 2 or 5 during the change-over operation.

During the time that the calling subscriber has been setting up the thousands and hundreds registers 110 and 120, the 75 tens and units registers 130 and 140 have been functioning to directly control the operation of the line selector in Fig. 2 to seize the calling line. At the time sequence switch 320 moves in position 2, a circuit is 80 closed as follows to drive sequence switch 350 out of position 1 and into position 2: from ground and battery, through the winding of sequence switch 350, contact 384 (1) and contact 337 (2) to ground. In position 85 2 of sequence switch 350, a cord finder switch whose brushes are shown at 313, 314, 315 and 316, individual to the register mechanism, is driven by means of power magnet 371 to select a line selector switch 90 having access to the group of lines containing the calling line. The circuit for power magnet 371 is traceable from ground and battery through the winding of said magnet, back contact and armature of relay 362 to 95 ground at contact 369 (2). When the test brush 316 reaches a test terminal 370 corresponding to an idle line selector having access to the proper group, a selectable potential is found on such terminal and the 100 following circuit established: on Fig. 2, from ground and battery, resistance 272, contact 271 (1) of sequence switch 250, conductor 230, terminal 370 on Fig. 3, brush 316, left-hand high resistance winding of 105 test relay 364 to ground at contact 369 (2). Test relay 364 energizes and closes a circuit over its low resistance right-hand winding, armature and contact, through the winding of the second test relay 362 to ground at 110 contact 369 (2) in parallel with the circuit traced through the left-hand high resistance winding of relay 364. This circuit reduces the potential on the multiples of terminal 370 so that no other finder switch will be 115 able to seize such terminals. Relay 362 by energizing opens the circuit of power magnet 371, bringing the brush carriage of the finder switch to rest. Relay 362 also closes the following circuit to drive sequence switch 350 over position 3 and into position 4: ground, contact 369 (2 to 3), armature and front contact of relay 362, through the winding of sequence switch magnet 350, 120 to battery and ground.

During the time the finder switch shown in Fig. 3 is being operated to associate the register controlling mechanism with an idle line selector, the units and tens registers 140 and 130 are being automatically positioned 125 130

in accordance with the units and tens digits of the calling line. For the purpose of adjusting the units register 140 to a position corresponding to the units digit of the calling line, the sequence switch 210 is adapted to run through a number of positions corresponding to the units digit of the calling line. The sequence switch 210 is provided with 20 positions, the first ten positions serving to control the setting of register 140 when the calling line belongs to the second ten lines of the sub-group of 20 as, for example, the line 199 in question. The second ten positions of sequence switch 210, namely positions 10 to 19, serve to control the setting of the units register 140 when the calling line belongs to the first ten lines of the group of 20 as, for example, the line 099. A relay 213 is provided for the purpose of starting sequence switch 210 from its position 0. The circuit for energizing relay 213 leads from grounded battery to the outer armature and front contact of relay 211, where it is closed, and further through the right-hand winding of relay 213, contact 290, (0) to ground at the lower armature and back contact of relay 239 assuming that the units relay 239 is not energized. When sequence switch 210 reaches position 1 the circuit of relay 213 is maintained over contact 290 (1), back contact and lower armature of relay 238 to ground at the lower armature of relay 239 assuming that relays 238 and 239 are not energized. When reaching position 2 the circuit of relay 213 is maintained over contact 291 (2), back contacts and lower armatures of relays 237, 238 and 239 to ground at relay 239, assuming that none of these relays are energized. In this manner the sequence switch 210 is driven from position to position until a units relay is found with its armatures attracted. In the case assumed, however, where line 199 is the calling line whose units digit is the tenth or No. 9 digit, the first relay 239 in the series is energized. Therefore, when relay 211 was energized no circuit was provided for relay 213 and consequently sequence switch 210 remained in its normal position 0. As soon as the relay 324 attracts its armature when the register controlling mechanism is seized the stepping relay 355 is energized as follows: from grounded battery, over contact 220 of sequence switch 210, left-hand armature and contact of relay 216, resistance 335, contact and inner armature of relay 324, contact 356, (1) of sequence switch 350, through the winding of relay 355 to ground at contact 358 (1). Relay 355 is energized and establishes a circuit from ground, contact and middle armature of relay 324, armature and front contact of relay 355, contact 353 (1), through the winding of relay 374 to battery and ground. Relay 374 is energized and provides a locking circuit for itself over its left-hand armature and contact 146 of units register 140. The registers 140 and 130 normally stand in position 1, being moved into this position as will be hereinafter described at the time the register controlling mechanism is restored to normal. The relay 374, which is for translating purposes, being energized at this time, later determines that the line selector in Fig. 2 will be driven over the first or even hundreds section of its terminal bank and into the second or odd hundreds section where the terminals of the line 199 appear.

As soon as sequence switch 350 moves into position 2, as has already been described, the following circuit is completed for the tens register 130: from grounded battery, through the winding of said register, contact 134 (1), contact 361 (2), back contact and armature of relay 366, front contact and armature of relay 355 to ground at contact 338 (2). The register 130 which, at this time, is standing in position 1 starts to rotate. Since the calling line belongs to the tenth or No. 9 group of 20 lines, relay 216 individual to this group is energized and battery potential from ground and battery of contact 220, is placed upon contact 136 in position 9 over left-hand armature and contact of relay 216 and the conductor 333. The tens register 130, therefore, continues to rotate until it reaches position 9, at which time a circuit is closed from grounded battery, contact 220 of sequence switch 210, left-hand armature and contact of relay 216, conductor 333, contact 136 (9) through the winding of relay 366 to ground. Relay 366 opens at its armature and back contact the above traced circuit for the tens register 130. Register 130 consequently stops in position 9. Relay 366 at its armature and front contact closes a circuit as follows from grounded battery over the slow operating relay 368; front contact and armature of relay 366, front contact and armature of relay 355 to ground at contact 338 of sequence switch 320. If sequence switch 350 has already reached position 4, after the finder switch has found an idle line selector or as soon as such sequence switch does reach position 4, the following circuit is established: ground, contact 377 (4) of sequence switch 350, armature and contact of relay 368 through the winding of sequence switch 350 to battery and ground. Sequence switch 350 thereupon moves into position 5.

In position 5 of sequence switch 350 the line selector, whose brushes are shown at 231, 232 and 233, is directly operated under the control of the tens and units registers 130 and 140 to the terminals 242, 243 and 244 of the calling line 199. For this purpose a fundamental circuit including step-

ping relay 355 and control relay 252 is established as follows: from grounded battery, to the winding of relay 252, contact 253 (1) of sequence switch 250, conductor 234, brush 314, contact and armature of relay 357, contact 356 (5) of sequence switch 350, through the winding of stepping relay 355 to ground at contact 358 (5). Relay 252 is energized and closes a circuit from ground and battery, through the winding of sequence switch 250, contact 254 (1) of this sequence switch to front contact, armature and ground at relay 252. Sequence switch 250 moves out of position 1 and into position 2. In leaving position 1, sequence switch 250 opens contact 271, the circuit leading over conductor 230, terminal 370, brush 316 and the left-hand winding of test relay 364 to ground at contact 369. In passing through position 1½ this sequence switch closes a circuit for the right-hand winding of relay 273, including contact 256 (1½) of sequence switch 250. Relay 273 is energized and at its left-hand armature and contact closes a circuit for its left-hand high resistance winding over conductor 230, and terminal 370, in series with the left-hand winding of relay 364 to contact 369 and ground. The relay 364 is unable to maintain its energization in series with the left-hand winding of relay 273 and therefore releases its armature. In position 2 of sequence switch 250, the tripping spindle power magnet 258 is energized over a circuit including contact 257 (2) and the front contact and armature of relay 252. The brush tripping spindle is thereby rotated and for each brush tripping position passed over, a short circuit is placed around the stepping relay 355 by means of the interrupter contact 255. Upon the first deenergization of the stepping relay 355, a circuit is completed from ground, contact 338, of sequence switch 320 armature and back contact of relay 355, left-hand winding and armature and contact of differential relay 359, contact 361 (5), contact 134, through the winding of the tens register 130, to battery and ground. The tens register 130 moves out of the position in which it is standing and by means of its local contact 131, short-circuits the left-hand winding of differential relay 359 permitting this relay to energize. When the short circuit is removed at the interrupter contact 255 and relay 355 is energized, the relay 359 releases its armatures in the manner already described in connection with the operation of relay 329. This operation continues until the tens register 130 reaches position 0, at which time a circuit is closed from grounded battery, through the winding of sequence switch 350, contact 373 (5), contact 134 (0), contact 361 (5), contact and armature and left-hand winding of relay 359, back contact and armature of relay

355 to ground at the sequence switch contact 338. The sequence switch 350, therefore, moves out of position 5 and into position 7.

In parallel with the circuit above traced 70 for sequence switch 350, a circuit is closed for relay 357. Relay 357 serves to open the fundamental circuit to prevent any further operation of the switch during the change-over period. As soon, after the 75 fundamental circuit is opened at the register mechanism, as the interrupter contact 255 is opened, the control relay 252 deenergizes and in so doing closes a circuit from ground over its armature and back contact, contact 254 (2), through the winding of sequence switch 250 to battery and ground whereby sequence switch 250 advances into position 3.

With the sequence switch 350 in position 7 the fundamental circuit is again closed 85 by contact 356 (7) at the controlling mechanism and relays 355 and 252 become again energized. Relay 252 at its front contact closes a circuit including contact 254 (3) for driving sequence switch 250 out of position 3 and into position 4. In position 4 of sequence switch 250, the brush carriage power magnet 261 of the line selector is energized in a circuit including contact 262 (4) and the back contact and armature of 90 relay 252. The brush carriage is rotated moving the selected set of brushes 231, 232 and 233 over the level of 20 terminals containing the terminals 242, 243 and 244 of the calling line. For each set of terminals 100 passed over the interrupter contact 267 connects the winding of relay 252 directly to ground in shunt of stepping relay 355. At the first closure of the contact 267, relay 355 releases its armature and closes a circuit 105 from ground, contact 338 of sequence 320, armature and back contact of relay 355, left-hand winding and armature and contact of relay 339, contact 367 (7) of sequence switch 350, contact 142 of the units register 140, through the winding of said register and battery to ground. The register 140 which, it will be remembered, is standing in position 1, the units digits of the calling line being 9, is energized in this 110 circuit and moves into position 2. When its local contact 143 closes between positions 1 and 2, the left-hand winding of differential relay 359 is shunted out and this relay is 115 energized by means of its right-hand winding. As interrupter contact 267 opens, the stepping relay 355 is energized opening the circuit of the right-hand winding of relay 359 causing said relay to release its armature. As the line selector brushes approach 120 the next set of terminals the interrupter contact 267 closes, relay 355 is deenergized and the above traced circuit is closed for the units register 140. The register 140 thereupon moves out of position 2 and into 125 130

position 3, and relay 359 attracts its armature as described. This method of operation continues the line selector brushes 231, 232, 233 advancing over one set of line terminals for each position through which the units register 140 passes. Upon the next deenergization of relay 355, after the units register 140 reaches position 0, the following circuit is closed for driving register 140 into position 1: ground, contact 338, armature and back contact of relay 355, left-hand winding, armature and contact of relay 359, contact 367 (7), contact 142 (0), right-hand armature and front contact of relay 374 through the winding of register 140 to battery and ground. Having passed position 0, the register 140 continues to rotate through an additional cycle coming to rest again in position 0 and, as a result, causes the line selector brushes to be advanced ten additional steps to the terminals 242, 243 and 244 of the calling line 199, which appear in the second or odd-hundreds section of the terminal bank. When register 140 passed from position 0 to position 1, ground was removed from contact 140 and relay 374 de-energized. Therefore as register 140 reaches position 0 at the end of its second rotation, a circuit is closed from grounded battery through the winding of sequence switch 350, contact 330, back contact and right-hand armature of relay 374, contact 142 (0), contact 367 (7), contact and armature and left-hand winding of relay 359, back contact and armature of relay 355, to contact 338 and ground. In parallel with this circuit, a circuit is also closed for the energization of relay 357 which serves to open the fundamental circuit. Sequence switch 350 being energized, advances from position 7 into position 8. When the interrupter contact 267 opens, after the opening of the fundamental circuit at the armature and contact of relay 357, the control relay 252 is de-energized and completes a circuit including contact 254 (4) for driving sequence switch 250 into position 5.

Thus, in response to the initiation of the call on line 199, an idle register controlling mechanism has been associated therewith, by means of the common connecting apparatus shown in Fig. 1, the selected idle controlling mechanism automatically associated with a line selector switch having access to the group containing the calling line, the tens and units digits of the calling line automatically registered on said controlling mechanism and the line selector switch directly operated, in accordance with such registration, to extend the calling line through to the circuits of a first group selector whose brushes are shown at 223, 224 and 225. During this operation which takes place in a very short period of time, the calling subscriber may be proceeding as

hereinbefore described to set up the thousands and hundreds registers of the controlling mechanism in accordance with the first two digits of the called line 200. Consider, for example, that the calling subscriber has just completed the sending of the first two series of impulses over the impulse circuit prepared by the common connecting apparatus shown in Fig. 1 to the stepping relay 325 when the line selector switch has completed its operation and sequence switches 250 and 350 have moved respectively into positions 5 and 8. That is to say, the thousands and hundreds registers 110 and 120 have been positioned by impulses sent from the calling sub-station over the impulse circuit which was immediately prepared by the common connecting apparatus at the initiation of the call. The calling line having been found by the line selector, however, this common connecting apparatus is no longer required and may now be released to the use of the other subscribers' lines in the group to which it is individual. Release of the common connecting means in Fig. 1 takes place at the time sequence switch 350 leaves position 7. On leaving position 7, contact 352 opens the closing circuit of relays 323, 216, 211 and 239 permitting these relays to deenergize. In the case assumed the sequence switch 210 is standing in position 0 and with relays 216, 211 and 239 deenergized, the common apparatus is completely restored and may be taken for use by another subscriber's line.

In order that the remaining registers 130 and 140 of the controlling mechanism may be set up in accordance with the called line number, a second impulse circuit from the calling substation to the stepping relay 325 is prepared over the terminals and brushes of the line selector switch. This circuit may be traced from ground and battery through the winding of stepping relay 325, contact 363 (8), brush 313, conductor 218, contact 263 (5), brush 232, terminal 243 over the loop of the calling line terminal 242, brush 231 to ground at contact 264 (5). It will be observed that the cut-off relay 207 was energized to disconnect the calling line from the common apparatus, Fig. 1, when sequence switch 250 moved into position 5. The circuit for cut-off relay 207 is traceable from ground and battery at and through the winding of said relay, contact 244, brush 233 to ground at contact 266 (5).

The calling subscriber, continuing to operate his sender, sends a series of impulses over the second impulse circuit corresponding to the tens digit. When relay 325 was energized at the time this impulse circuit was first established, a circuit was completed from ground over the armature and front contact of said relay, armature and contact relay 331, left-hand winding, arms

ture and contact of relay 329, contact 311 of sequence switch 320, which, it will be remembered, is standing in position 8, through the winding of register 130 to battery and ground. The register 130 having been brought to position 0, as was explained, in controlling the operation of the line selector switch, is advanced into position 1 at its local contact. This register closes a shunt at its local contact around the left-hand winding of relay 329 permitting said relay to be energized. When the line circuit is opened on the first impulse in the tens series, relay 325 is deenergized, causing in turn the deenergization of differential relay 329. At the next closure of the line circuit the register 130 advances from position 1 to position 2 and so on for each succeeding impulse, coming finally to rest in a position corresponding to the tens digit of the desired line. On the last comparatively long interruption of the line circuit at the end of the tens series, relay 325 releases its armature for an interval sufficient to allow the energization of the slow operating relay 334. Relay 334 closes a circuit to drive sequence switch 320 out of position 8. Relay 334 is soon deenergized, due to the closure of the line circuit, so that sequence switch 320 comes to rest when it reaches position 11.

In position 11 of sequence switch 320, the following circuit is closed: from ground, to armature and front contact of relay 325, armature and contact of relay 331, left-hand winding, armature and contact of relay 329, contact 312 (11) to the winding of the units register 140 to battery and ground. The units register 140 which, like the tens register, was left in position 0 at the end of line selection, is energized and moves into position 1. On passing to position 1 this register at its local contact shunts out the left-hand winding of relay 329 permitting said relay to attract its armature by means of a circuit closed through its right-hand winding. When the calling line is opened for the first impulse in the units series, stepping relay 325 releases its armature and opens the circuit of the right-hand winding of relay 329. Relay 329 thereupon is deenergized. When the line circuit is again closed and relay 325 attracts its armature, the units register 140 is again energized and advances into position 2. This procedure continues, the units register moving from position to position until the last impulse in the series has been sent. The last interruption being comparatively long, relay 334 is energized as explained and sequence switch 320 advances from position 11 into position 14.

The brush tripping operation of the first group selector takes place immediately upon the controlling mechanism having been associated therewith, provided the calling

subscriber has, at this time, completed the registration of the thousands digit on the register 110. The register 110 having been positioned, it will be recalled that sequence switch 320 thereupon moves from position 2 into position 5. If, at this time, the sequence switch 350 has reached position 8, the following circuit is closed to drive said sequence switch into position 10: from ground to battery through the winding of sequence switch 350, contact 384 (8) and contact 337 (5) to ground. In position 10 of sequence switch 350 the usual fundamental circuit for controlling the brush tripping operation of the first group selector is again completed as follows: from grounded battery, through the winding of relay 252, contact 253, conductor 234, brush 314, contact and armature of relay 357, contact 356 (10), through the winding of stepping relay 355 to ground at contact 358. Relays 355 and 252 are energized in this circuit. At the armature and front contact of relay 252 a circuit is closed including contact 254 (5) for driving sequence switch 250 into position 6. In position 6 of sequence switch 250 the brush tripping spindle power magnet 278 of the first group selector is energized over the following circuit: from grounded battery, through the winding of power magnet 278, contact 276 (6) to front contact and armature of relay 252 and ground. The brush tripping spindle rotates and for each tripping position the winding of relay 252 is connected direct to ground by means of a circuit including contact 259 (6) and the interrupter contact 275. This direct circuit to ground shunts out the stepping relay 355 in the fundamental circuit causing said relay to be deenergized. Upon the first deenergization of relay 355 a circuit is closed from ground, contact 338, armature and back contact of relay 355, left-hand winding and armature and contact of relay 359, contact 367 (10), right-hand armature and back contact of relay 376, contact 114, through the winding of the thousands register 110 to battery and ground. The thousands register moves from the position to which it was adjusted by the called subscriber's sender to the next succeeding position. At its local contact 111 the register 110 shunts out the left-hand winding of relay 359 permitting this relay to energize. When the interrupter contact 275 is opened, relay 355 is again energized causing in turn the deenergization of the differential relay 359.

On each succeeding deenergization of the relay 355 the thousands register is advanced from position to position until it reaches position 0. On the following deenergization of relay 355, after the thousands register has reached position 0, a circuit is closed from grounded battery through the winding of sequence switch 350, contact 373 (10),

switch 320 moves into position 14, the sequence switch 350 is advanced from position 15 into position 17. The circuit for driving sequence switch 350 into position 17 includes 5 contact 380 and contact 340. In position 17 of sequence switch 350 the fundamental circuit is again established ready to control the units selection at the final selector 251. As the stepping relay 355 is deenergized in the 10 well-known manner for each set of terminals passed over by the selected set of brushes, the following circuit is closed: ground, contact 338, armature and back contact of relay 355, left-hand winding, armature and front contact of relay 359, contact 367 (17), contact 142 through the winding of register 140 to battery and ground. The register 140 advances from one position to the next and upon reaching position 0, the following circuit 15 is closed: from grounded battery, through the winding of sequence switch 350, contact 330 (17), back contact and right-hand armature of relay 374, contact 142 (0) contact 367 (17), contact armature and left-hand winding of relay 359, back contact and armature of relay 355, to contact 338 and ground. Sequence switch 350 moves from 20 position 17 into position 1.

When sequence switch 350 reaches position 1 a circuit is closed for driving sequence switch 320 back to its nominal position. This 25 circuit includes contact 332 (14 to 15) and contact 310 (1). When sequence switch 320 passes through position 16 it closes a circuit 30 at contact 336 for the tens register 130. This register, therefore, moves from position 0 into position 1 where it is found when the register-controlling mechanism is taken for 35 use by a calling line. Likewise the units register 140 is driven from position 0 into position 1 by means of a circuit momentarily 40 closed at contact 336 as sequence switch 320 passes through position 17. The register-controlling mechanism is now completely 45 restored to its normal condition ready for use in connection with subsequent calls.

As sequence switch 350 leaves position 17 it opens at contact 369 the above-traced circuit of relay 273. Relay 273 being deenergized, closes a circuit from grounded battery, through the winding of sequence switch 250, contact 260 (9) back contact and armature of supervisory relay 274, to the right-hand armature and contact of relay 273 and ground. Sequence switch 250, therefore 50 passes over position 11 and comes to rest in position 12. When the called subscriber answers, the supervisory relay 274 is energized in series with the called line and the right-hand windings of the repeating coil 269. At its armature and front contact relay 274 closes a circuit including contact 254 (12) to drive sequence switch 250 into position 13, which is the talking position thereof. The calling line is thus extended over 55

sequence switch contacts 263 and 264 through to the left-hand windings of the repeating coil 269 and conversation may take place. In position 13 of sequence switch 250 a circuit is closed from grounded battery to resistance 272, contact 271 (13), to the winding of relay 277 and ground. The relay 277 which is slow to attract its armatures, energizes after the lapse of a definite interval. 70

At the end of the conversation when the receivers are replaced to the switchhook, relays 268 and 274 are deenergized and relay 268 closes a circuit for relay 252 including contact 253 (13). Relay 252 in turn completes a circuit over its armature and front contact and contact 254 (13) for driving sequence switch 250 into position 17. In passing through positions 14 and 16, sequence switch 250 closes the following circuit: from ground and positive pole of battery, contact and left-hand armature of relay 277, contact 266 (14 to 16), brush 233, terminal 244, through the winding of message register magnet 305 through the negative pole of 80 battery and ground. The register 305 is 85 therefore operated to charge the call to the calling line.

In position 17 of sequence switch 350 the slow-operating relay 277 which, up to this time, is locked up over a circuit including its contact and right-hand armature, is short-circuited by the ground at contact 256. Relay 277, therefore, is deenergized. The brush carriage of the line selector is now restored to normal by means of a circuit from grounded battery through the winding of power magnet 261, contact 262 (17), back contact and armature of relay 252 to ground. As the brush carriage reaches its home position, relay 252 is energized in a circuit including contact 259 (17), and brush 206. Relay 252 closes a circuit including contact 254 (17) for driving sequence switch 250 into position 18. 100 In position 18, the brush carriage of the first group selector is returned to its normal position by means of a circuit from grounded battery through the winding of brush carriage power magnet 281, back contact 105 and armature of relay 282, to contact 283 and ground. When the first group selector brush carriage has been completely restored, a circuit is established from grounded battery through the winding of magnet 109, 110 contact 286 (18), brush 208 and its home contact, through the winding of relay 282, to contact 283 (18) and ground. Relay 282 attracts its armature and closes a circuit 115 including contact 283 for driving sequence switch 250 back to its normal position 1. Release of the succeeding selectors 235 and 251 takes place in the well-known manner. 120

Had the called line 200 been busy at the time the final selector completed its units 125

contact 112 (0), back contact and right-hand armature of relay 376, contact 367 (10), contact and armature and left-hand winding of relay 359, back contact and 5 armature of relay 355, to contact 338 and ground. In parallel with this circuit a circuit is also completed for relay 357. Relay 357 opens the fundamental circuit while sequence switch 350 energizes and moves from 10 position 10 into position 11. The brush tripping spindle has now been rotated to a position for tripping the proper set of brushes and the fundamental circuit is opened at the register controlling mechanism as register 110 reaches position 0. The next opening of the interrupter contact 275 permits the control relay 252 to be de-energized. Relay 252 closes a circuit over its armature and back contact and contact 15 254 (6) for driving sequence switch 250 out of position 6 and into position 7.

The selected set of brushes 223, 224 and 225 are next driven over the level of trunk terminals leading to second group selectors 20 such as the selector shown at 235. For this purpose the brush carriage power magnet 281 is energized in a circuit from grounded battery through the winding of said magnet, back contact and armature of relay 282, to ground at contact 283 (7). When the test brush 225 of the first selector engages a terminal 226 having a selectable potential thereon, the test relay 284 is energized in a circuit through its left-hand winding to ground at contact 283. Relay 284 attracts its armature and closes a low resistance path through its right-hand winding and the winding of relay 282 to ground at contact 283. This low resistance circuit decreases 30 the potential on terminal 226 sufficiently to render the same non-selectable to other first group selectors. The relay 282 which is energized at the same time, opens the circuit of the power magnet 281, bringing the brush carriage to rest. A circuit is also completed for sequence switch 250 from 35 grounded battery through the winding of sequence switch 250, front contact and armature of relay 282 to ground at contact 283.

Sequence switch 250 advances from position 40 7 over position 8 and into position 9.

If at this time the calling subscriber has completed the setting of the second or hundreds register 120, sequence switch 320 will 45 have been driven into position 8. Hence a circuit is established from grounded battery through the winding of sequence switch 350, contact 365 (11), contact 339 (8) to ground. Sequence switch 350 thereupon moves from position 11 into position 13. The fundamental circuit is again closed from the register controlling mechanism through to the second group selector 235. This circuit leads from the second group selector 50 over brush 223, contact 289 (9), conductor 240, brush 315, contact 358 (13), through the winding of stepping magnet 355, contact 356 (13), armature and contact of relay 357, brush 314, conductor 234, contact 288 (9), and thence over brush 224 to the second group selector. In the well-known manner the brush tripping operation at this selector switch takes place under the control of the hundreds register 120. For each shunting of the stepping relay 355, during 55 the rotation of the brush tripping spindle, the register 120 is advanced from one position to another by means of the following circuit: ground, contact 338, armature and back contact of relay 355, left-hand winding, armature and contact of relay 359, contact 381 (13), contact 124, through the winding of register 120 to battery and ground. On reaching position 0, the register 120 closes a circuit traceable from 60 grounded battery, through the winding of sequence switch 350, contact 373 (13), contact 112 (0), contact 124 (0), contact 381 (13), contact and armature and left-hand winding of relay 359, back contact and armature of relay 355, to contact 338 and ground. Sequence switch 350 thereby moves into position 14. Trunk hunting now takes place at the second group selector and a trunk is selected leading to an idle final 65 selector switch such as the one shown at 251.

Provided the calling subscriber has completed the setting of the tens register 130, at this time, sequence switch 320 will have been moved into position 11. Consequently 70 sequence switch 350 is driven out of position 14 and into position 15 by means of a circuit including contact 365 (14) and contact 339. In position 15 of sequence switch 350 the fundamental circuit is closed at contact 356 and extends through to the final selector switch 251. Brush selection takes place at the final selector, under the control of the tens register 130, the stepping relay 355 being deenergized for each brush-tripping position passed over by the tripping spindle. At each deenergization of relay 355 the tens register is advanced from one position to another by means of the following circuit: ground, contact 338, armature 75 and back contact of relay 355, left-hand winding, armature and contact of relay 359, contact 361 (5), contact 134, through the winding of tens register 130, to battery and ground. When register 130 reaches position 0 the sequence switch 350 is moved into position 16 by means of a circuit from grounded battery through the winding of sequence switch 350, contact 373 (15), contact 134 (0), contact 361 (5), contact, armature and left-hand winding of relay 359, back contact and armature of relay 355, to contact 338 and ground.

Assuming that the units register 140 has already been positioned, when sequence 80

selection, the relay 274 would not have operated in series with said line. Therefore, sequence switch 250 remains in position 12 and the slow-operating relay 277 is not energized. When the calling subscriber replaces the receiver to the switchhook and relay 252 is energized as explained, sequence switch 250 advances from position 12 directly into position 17. In passing through position 13, the circuit of relay 277 is not closed for a sufficient length of time to permit this relay to attract its armatures. Therefore, in passing through positions 14 to 16, the sequence switch contact 266 is without effect to apply metering current to the third conductor of the calling line and message register 205 is not operated to charge the call.

It will now be assumed that the subscriber's line 099 belonging to the even-hundred group, and which corresponds to the line 199 in the same sub-group of 20 lines, initiates a call. In this case the line relay 202 is energized instead of relay 201. Relay 202 closes a circuit from grounded battery, outer armature and back contact of relay 211, winding of relay 212, through the right-hand winding of relay 214, contact and right-hand armature of relay 202 to upper winding of relay 239 and ground. Relay 239 is energized and closes a circuit over its lower armature and contact through its lower winding, left-hand armature, front contact and left-hand winding of relay 214, through the winding of relay 215, to inner armature and contact of relay 211 to battery and ground. Relay 215 closes a circuit as hereinbefore described, to select an idle controlling mechanism. When relay 216 is energized to associate the calling line with the controlling mechanism the left-hand winding of relay 214 is included in the circuit with the right-hand winding of relay 216. Relay 211 also energizes at this time and since relay 214 is energized, the following circuit is established for relay 213: from grounded battery, to outer armature and front contact of relay 211, left-hand winding of relay 213, contact 222 (0), to outer right-hand armature and contact of relay 214 and ground. Relay 213 at its armature and contact closes a circuit for sequence switch 210 which passes from position 0 to position 10, disregarding which of the units relays 236 to 239 is energized. On reaching position 10, the circuit of the left-hand winding of relay 213 is opened at contact 222 and since relay 239 is the one which is energized, no circuit exists over the contact 290 for the right-hand winding of relay 213, therefore, this relay releases its armature and causes sequence switch 210 to stop in position 10.

As hereinbefore explained the relay 374 was energized and locked up when sequence

switch 320 moved into position 2 by means of a circuit closed at the armature and front contact of relay 355. When sequence switch 210 passes from position 0 to position 1, it opens at contact 220 the above-traced circuit for relay 355. This relay at its armature and back contact closes a circuit from grounded battery through the winding of the units register 140, contact 142, contact 367, contact and armature and left-hand winding of relay 359, contact and armature of relay 355, to contact 338 and ground. The register 140 advances from position 1 into position 2. The opening of contact 220 as sequence switch 210 passes from position 1 to position 2 causes a second deenergization of relay 355 which results in register 140 being driven from position 2 to position 3. This operation continues, the register 140 being moved from one position to another until sequence switch 210 reaches position 10. At this time register 140 has been returned to position 1 and on passing from position 0 to position 1, register 140 opens the locking circuit of relay 374 at contact 146, permitting this relay to release its armatures. The relay 374 being deenergized, the register 140 stops in position 0 instead of running through an additional cycle when it later becomes effective to control units selective operation of the line selector switch. By this expedient the brushes 231, 232 and 233 of the line selector are caused to stop on the terminals of the calling line 099 which appear in the first of the even hundreds section of the terminal bank. From this point on the operation is the same as that described in detail in connection with the initiation of a call on line 199.

Assuming next that the calling lines instead of being the tenth or twentieth line in the sub-group of 20, as in the cases discussed, had been either the eighth or eighteenth lines, for example, the units digits of these lines would, therefore be 7, and relay 237 is the relay that would be taken for use when either of such lines initiates a call. When relay 211 is energized, a circuit is first closed as follows for the right-hand winding of relay 213: from grounded battery, to outer armature and front contact of relay 211, through the right-hand winding of relay 213, contact 290 (0), to back contact and lower armature of relay 239 and ground. Relay 213 is energized and closes a circuit to drive sequence switch 210 out of position 0 and into position 1. In position 1 sequence switch 210 continues to rotate since relay 213 maintains its energization in a circuit over contact 290 (1) and the back contacts and lower armatures of relays 238 and 239. When, however, sequence switch 210 reaches position 2, it comes to rest since relay 237 is energized and relay 213 fails to find a holding circuit

- for its right-hand winding over sequence switch contact 291 (2). During the time that sequence switch 210 is passing from position 0 to position 2 its contact 220 interrupts the circuit of relay 355 which in turn causes the units register 140 to be advanced as already described to a position corresponding to the units digit of the calling line.
- 10 When the common connecting means shown in Fig. 1 is released, after the calling subscriber's line has been selected under the control of the tens and units registers 130 and 140, relay 211 does not deenergize as 15 was the case when sequence switch 210 remained in position 0. Instead relay 211 maintains its armature attracted by means of an energizing circuit from ground and battery, through its right-hand winding to contact 221 and ground, closed in some position from 1 to 19. Hence when relay 237 releases its armatures, a circuit is established from ground and battery to outer armature and front contact of relay 211, through the 20 right-hand winding of relay 213, contact 291 (2), back contacts and armatures of relays 237, 238 and 239 to ground. Relay 213 attracts its armature and closes a circuit to drive sequence switch 210 out of position 2 25 and into position 0. Relay 213 maintains its energization during the rotation of sequence switch 210 over a circuit including contacts 290, 291, 292 and 293 and back contacts and armatures of relays 236, 237, 238 30 and 239. On passing out of position 19 sequence switch contact 221 opens the circuit of relay 211, permitting this relay to be deenergized which in turn causes the deenergization of relay 213. Sequence switch 210, 35 therefore, comes to rest in position 0 and the common connecting apparatus is ready to be taken for another call.
- In order that the register-controlling mechanism, which is positioned by impulses 40 transmitted in accordance with the decimal system of numbers, may be adapted to deliver impulses for controlling the operation of the selector switches, in accordance with the system on which switches of this character are operated, relays 374 and 376 are 45 provided for accomplishing the necessary translation. Should the thousands digit of the called line be odd, the contact 115 is connected to ground as soon as the thousands register 110 has been positioned from 50 the calling subscriber's sender. When sequence switch 350 passes from position 8 to position 10 it closes in position 9 the following circuit: from grounded battery, 55 through the winding of relay 376, contact 378 (9), contact 115, to ground. Relay 376 attracts its armatures and provides a locking circuit for itself over its left-hand armature and contact and contact 377. 60 With relay 376 energized and sequence 65 switch 350 in position 10, the thousands register 110 is operated over the following circuit to control the brush tripping operation of the first group selector: from ground and battery, at and through the winding of register 110, contact 114, front contact and right-hand armature of relay 376, contact 367 (10), and thence to ground as above described, at sequence switch contact 338. Since the contact 114 is closed only in positions 1 to 8, inclusive, the register 110 comes to rest in position 9 rather than in position 0. The result is that the same level of terminals is selected at the first group selector for this particular odd-thousands 70 digit as would have been chosen had the thousands digit been the next lower even digit. Sequence switch 350 now advances into position 13 where brush selection takes place at the second group selector, under the control of the hundreds register 120. Register 120 is advanced from its set position to position 0 in the manner already described. In position 0 of register 120 the thousands register 110 is now moved from position 9 into position 0 by means of the following circuit: from grounded battery, through the winding of register 110, contact 112, contact 124 (0), contact 381 (13), and thence to sequence switch contact 338 and 75 ground. This additional step of the thousands register 110 results in the rotation through an additional position of the second group selector brush tripping spindle. Therefore, a level of trunks is selected leading to final selectors having access to the proper odd-thousands group. With the register 110 in position 0, sequence switch 350 is driven from position 13 into position 90 14 by means of the circuit hereinbefore 105 traced.
- Should the hundreds digit of the called line be odd, contact 126 of the hundreds register is connected to ground and relay 374 is energized over a circuit including 110 contact 353 as sequence switch 350 passes through position 12. Relay 374 locks up in a circuit from grounded battery through its winding, left-hand contact and armature and contact 146 to ground. When the units register 140 reaches position 0 during the units selection at the final selector 251, the sequence switch 350 is not driven out of position 17 as before, since the relay 374 is now energized. Register 140 is, therefore, 115 energized over the following circuit and leaving position 0 makes a complete additional cycle of operation: from grounded battery, through the winding of said register, front contact and right-hand armature of relay 374, contact 142 (0), contact 367 (17), and thence to sequence switch contact 338 and ground. This additional cycle of the units register causes the selected set of brushes at the final selector to be advanced 120 125 130

over the first section of the terminal bank and onto the terminals of the called line in the second or odd-hundreds section of said bank. As register 140 passes from position 0 to position 1 contact 146 is opened and relay 374 deenergized. Hence when register 140 again comes into position 0 it ceases to rotate.

What is claimed is:

- 10 1. In a telephone system, a calling line, a line selector and group selectors for extending said line, a register controlling mechanism for controlling the operation of said selectors, means responsive to the initiation of a call on said line for associating said mechanism therewith, means for operating the line selector to select the calling line, an impulse circuit established upon the association of said mechanism with said line, a second impulse circuit established when the line selector has selected the calling line, means controlled by the calling subscriber for sending impulses over both of said circuits, and means responsive to such impulses for setting said controlling mechanism.

15 2. In a telephone system, a calling line, a line selector and group selectors for extending said line, a register controlling mechanism for controlling the operation of said selectors, means responsive to the initiation of a call on said line for associating said mechanism therewith, means for operating the line selector to select the calling line, an impulse circuit established upon the association of said mechanism with said line, a second impulse circuit established over the line selector as soon as said line selector has selected the calling line, means controlled by the calling subscriber for sending impulses over both of said circuits, and means responsive to such impulses for setting said controlling mechanism.

20 3. In a telephone system, a calling line, a line selector and group selectors for extending said line, a register controlling mechanism for controlling the operation of said selectors, means responsive to the initiation of a call on said line for associating said mechanism therewith, means for operating the line selector to select the calling line, an impulse circuit established upon the association of said mechanism with said line, a second impulse circuit established when the line selector has selected the calling line and for sending impulses over said second circuit after said line is selected, and means responsive to the impulses sent over said second circuit for completing the setting of said mechanism.

25 4. In a telephone system, a calling line, a line selector and group selectors for extending said line, controlling mechanism comprising a plurality of registers for controlling the operation of said selectors, means responsive to the initiation of the call on said line for associating said mechanism therewith, means for operating the line selector to select the calling line, an impulse circuit established upon the association of said mechanism with said line, a second impulse circuit established when the line selector has selected the calling line, means controlled by the calling subscriber for sending impulses over said first circuit while the line selector is selecting the calling line and for sending impulses over said second circuit after said line is selected, and means responsive to the impulses sent over said first circuit for setting certain of said registers, said last named means being responsive to the impulses sent over said second circuit for setting the remainder of said registers.

30 5. In a telephone system, a group of lines, a line selector and group selectors for extending said lines, a register controlling mechanism for controlling the operation of said selectors, connecting means common to the lines of said group, said connecting means being responsive to the initiation of a call on one of said lines for connecting said controlling mechanism to such line, means for operating said line selector to select the calling line, an impulse circuit established by said connecting means, a second impulse circuit established by the line selector after the calling line is selected, means for sending impulses over said first circuit while said line selector is operating and for sending impulses over said second circuit after the line selector has completed its operation, and means responsive to such impulses for setting said controlling mechanism.

35 6. In a telephone system, a group of lines, a line selector and group selectors for extending said lines, a register controlling mechanism for controlling the operation of said selectors, connecting means common to the lines of said group, said connecting means being responsive to the initiation of a call on one of said lines for connecting said controlling mechanism to such line, means for operating said line selector to select the calling line, an impulse circuit established by said connecting means, a second impulse circuit established by the line selector after the calling line is selected, means for sending impulses over said first circuit while said line selector is operating and for sending impulses over said second circuit after the line selector has completed its operation, and means responsive to such impulses for setting said controlling mechanism.

40 7. In a telephone system, a group of lines, divided into sub-groups, a line selector and

- group selectors for extending said lines, a register controlling mechanism for controlling the operation of said selectors, a plurality of connecting means each individual to one of said sub-groups, each connecting means being responsive to the initiation of a call on a line in the corresponding sub-group for connecting said mechanism to such line, means for operating said line selector to select the calling line, an impulse circuit established by said connecting means while said line selector is in operation, a second impulse circuit established by the line selector at the completion of its operation, means for sending impulses first over one and then over the other of said circuits, and means responsive to such impulses for setting said controlling mechanism.

8. In a telephone system, a group of lines, a line selector and group selectors for extending said lines, a register controlling mechanism for controlling the operation of said selectors, connecting means common to the lines of said group, said connecting means being responsive to the initiation of a call on one of said lines for connecting said mechanism to such line, means for operating the line selector to select the calling line, an impulse circuit established by said connecting means during the operation of the line selector, means for releasing said connecting means as soon as the line selector has completed its operation, a second impulse circuit established by the line selector at the completion of its operation, means for sending impulses over both of said circuits, and means responsive to such impulses for setting said controlling mechanism.

9. In a telephone system, a group of lines, a line selector and group selectors for extending said lines, controlling mechanism comprising a plurality of registers for controlling the operation of said selectors, connecting means common to the lines of said group, said connecting means being responsive to the initiation of a call on one of said lines for connecting said mechanism to such lines, means for operating the line selector to select the calling line, an impulse circuit established by said connecting means during the operation of the line selector, means for releasing said connecting means as soon as the line selector has completed its operation, a second impulse circuit established by the line selector at the completion of its operation, means controlled by the calling subscriber for sending impulses first over one and then over the other of said circuits, and means responsive to the impulses sent over said first circuit for setting certain of said registers, said last-named means being responsive to the impulses sent over said second circuit for setting the remainder of said registers.

10. In a telephone system, a calling line, a line selector and group selectors for extending said line, a register controlling mechanism for controlling the operation of said selectors, means responsive to the initiation of a call on said line for associating said mechanism therewith, means for associating said mechanism with said line selector, means for operating said line selector to select the calling line, an impulse circuit for sending impulses over the calling line to said mechanism while the line selector is selecting said line, a second impulse circuit established upon the selection of the calling line for sending impulses over said line to said mechanism, and means responsive to such impulses for setting said mechanism.

11. In a telephone system, a calling line, a line selector and group selectors for extending said line, a register controlling mechanism for controlling the operation of said selectors, means responsive to the initiation of a call on said line for associating said mechanism therewith, a finder switch for associating said mechanism with said line selector, means for operating said line selector to select the calling line, an impulse circuit for sending impulses over the calling line to said mechanism while the line selector is selecting said line, a second impulse circuit established upon the selection of the calling line for sending impulses over said line to said mechanism, and means responsive to such impulses for setting said mechanism.

12. In a telephone system, a calling line, a plurality of line selectors and group selectors for extending said line, a register controlling mechanism for controlling the operation of said selectors, means responsive to the initiation of a call on said line for associating said mechanism therewith, a finder switch for associating said mechanism with an idle one of said line selectors, means for operating said line selector to select the calling line, an impulse circuit for sending impulses over the calling line to said mechanism while the line selector is selecting said line, a second impulse circuit established upon the selection of the calling line for sending impulses over said line to said mechanism, and means responsive to such impulses for setting said mechanism.

13. In a telephone system, a calling line, a line selector and group selectors for extending said line, controlling mechanism, means responsive to the initiation of a call on said line for associating said mechanism therewith, means for registering the designation of said line on said mechanism, means controlled by said mechanism

- in accordance with the designation registered for operating said line selector to select the calling line, means for setting a portion of said mechanism in accordance with 5 a desired designation during the operation of the line selector, means established by the line selector at the end of its operation for completing the setting of said mechanism in accordance with the desired designation, and means controlled by said mechanism in accordance with the desired designation for operating said group selectors.
14. In a telephone system, a calling line, a line selector and group selectors for extending said line, controlling mechanism, means responsive to the initiation of a call on said line for associating said mechanism therewith, means operated automatically upon the association of said mechanism with 10 the calling line for registering the designation of said line on said mechanism, means controlled by said mechanism in accordance with the designation registered for operating said line selector to select the calling line, means for setting a portion of said mechanism in accordance with a desired designation during the operation of the line selector, means established by the line selector at the end of its operation for completing the setting of said mechanism in accordance with the desired designation, and means controlled by said mechanism in accordance with the desired designation for operating said group selectors.
15. In a telephone system, a calling line, a plurality of line selectors and group selectors for extending said line, controlling mechanism, means responsive to the initiation of a call on said line for associating 15 said mechanism therewith, means for associating said mechanism with an idle one of said selectors, means for registering the designation of said line on said mechanism, means controlled by said mechanism in accordance with the designation registered for operating said line selector to select the calling line, means for setting a portion of said mechanism in accordance with a desired designation during the operation of the line selector, means established by the line selector at the end of its operation for completing the setting of said mechanism in accordance with the desired designation, and means controlled by said mechanism in accordance with the desired designation for operating said group selectors.
16. In a telephone system, a calling line, a plurality of line selectors and group selectors for extending said line, controlling mechanism, means responsive to the initiation of a call on said line for associating 20 said mechanism therewith, means for positioning a portion of said registers according to the designation of said line, means controlled by said positioned registers for operating the line selector to select the calling line, means for positioning the remainder of said registers in accordance with a desired designation, means for repositioning said first positioned registers in accordance with the desired designation, and means controlled by said registers for operating said group selectors in accordance with said desired designation.
17. In a telephone system, a calling line, line selectors and group selectors for extending said line, controlling mechanism comprising a plurality of registers, means responsive to the initiation of a call on said line for associating said mechanism therewith, means for positioning a portion of said registers according to the designation of said line, means controlled by said positioned registers for operating the line selector to select the calling line, means for positioning the remainder of said registers in accordance with a desired designation, means for repositioning said first positioned registers in accordance with the desired designation, and means controlled by said registers for operating said group selectors in accordance with said desired designation.
18. In a telephone system, a calling line, line selectors and group selectors for extending said line, controlling mechanism comprising a plurality of registers, means responsive to the initiation of a call on said line for associating said mechanism therewith, means for positioning a portion of said registers according to the designation of said line, means controlled by said positioned registers for operating the line selector to select the calling line, means for positioning the remainder of said registers in accordance with a desired designation, means for repositioning said first positioned registers in accordance with the desired designation, and means controlled by said registers for operating said group selectors in accordance with said desired designation.

In witness whereof, I hereunto subscribe my name this 11th day of October A. D., 1919.

LIPA POLINKOWSKY.
